UNITED STATES PATENT OFFICE.

CHARLES FINK, OF BALTIMORE, MARYLAND.

ADJUSTABLE ROUTER.

1,195,799.

Specification of Letters Patent. Patented Aug. 22, 1916.

Application filed June 30, 1914. Serial No. 848,268.

To all whom it may concern:

Be it known that I, CHARLES FINK, citizen of the United States, residing at Baltimore, Maryland, have invented certain new and useful Improvements in Adjustable Routers, of which the following is a specification.

The present invention relates to bench planes and pertains more particularly to that class of planes known as routers, which are adapted to be used in cutting out square or rectangular recesses. This type of plane is of special value in forming recessed places along the edges of doors or windows in which metal plates, such as hinge plates, are adapted to be countersunk.

The principal object of the invention consists in providing a router plane of the class above described, having the usual form of vertically adjustable cutting tool and being formed of two sections hinged together in such manner as to provide an additional secondary adjustment of the parts.

With these and other objects the invention consists in the combination and arrangement of parts more fully set forth in the following specification, illustrated in the accompanying drawings and pointed out in the appended claims.

In the drawings: Figure 1 is a longitudinal section with parts in elevation, Fig. 2 is a plan view. Fig. 3 is a transverse sectional view on line 3—3 of Fig. 2.

Referring to the drawings, the router consists of an inner section 1, and an outer section 2 adapted to fit one within the other and hinged together at the back of the tool. The two side pieces of the outer section 2 are formed with perforated ear pieces 3 at their rear ends. The inner section 1 is provided with an integral upturned end piece 4 formed at right angles to the lower edge of the tool and having a horizontal bore 4^a near its lower end. A pin 5 passing through the perforations in the ear pieces 3 and the bore 4^a form a swiveled, hinged connection between the two sections of the plane.

The inner section 1 is provided with a transverse plate 6 located midway of its length from which is centrally supported a vertical tool post 7. The tool post is formed with an angular groove extending up its front face against which the rear edge of the cutting tool 8 is clamped. A screw stud 9 is screwed rigidly into the tool post

7 and carries an adjustable knurled nut 10 threaded thereon, which latter registers in a notch 11 in the rear edge of the tool shank. A clamping member 12 is provided having a yoke piece 13 at its forward end passing around the tool 8 and tool post 7. The clamping member 12 extends horizontally and passes through a perforation 4^b formed in the upturned end piece 4. A knob 14 having an internal nut 15 securely fastened therein is screw-threaded on the projecting end of the clamping member 12, as shown in Fig. 1. The stem portion of the clamping piece 12 intermediate of the tool post 7 and upright 4 is flattened and has riveted thereto wooden pieces 16 to form a suitable handle.

Both the inner and outer section pieces are formed with openings 18 through which the cutting tool 8 extends. These are made of suitable size and shape to allow the shavings cut to pass upward from the cutting edge of the tool.

The two sections are held together near the forward part of the tool by a coiled spring 17 contained within a hollow boss 18 formed on the inner section 1. A screw post 19 having an upper shoulder 20 is centrally fastened within the boss 18 and is rigidly secured at its lower end to the outer section 1. The coiled spring 17 which surrounds this post has its lower end bearing on the inner section 2 and its upper end against the shoulder 20 tends to keep the two sections together.

The secondary adjustment of the router consists of a vertical adjusting post 21 screw threaded into a boss 22 formed near the front end of the inner section 1. The upper end of the post carries the knob piece 23 by which it is easily manipulated and has its lower end passing through a hole 24 in the inner section 1 and bearing on the outer section 2.

In operation the two sections of the router are first brought together. The tool 8 is then set to the required depth to be routed out below the surface by means of the adjusting nut 11 and the clamping piece 12 tightened by the knob 15. The surface to be routed out is first roughened out to within, say three sixteenths of an inch of the required depth. The two sections are then opened by means of the secondary adjustment screw 21 until the tool 8 just touches

the roughened surface. The finishing of the cut is done by degrees by giving the knob 23 slight turns, thereby taking light cuts in succession until the two sections are again brought together. It will be seen that the tool will have cut the full depth required.

Having described my invention what I claim is:

10. 1. A router plane comprising in combination plane body and sole members extending substantially parallel throughout the length of the plane, a hinged connection between said members at one end, spring-held means connecting said members near the opposite end tending to hold the members together, an adjustable cutting tool carried by said inner member and adjusting means at the forward end of the plane operating at right angles to the base of the plane for opening said members from each other, substantially as described.
15. 2. A router bench plane comprising in combination plane body and sole members extending substantially parallel throughout the length of the plane, a hinged connection between said members at the rearward end,

spring held means connecting said members near the forward end tending to hold the members together, an adjustable cutting tool carried by said plane body member and adjusting means operating at right angles to the base of the plane for opening said members from each other, said means being located at the forward end of the plane and embodying a handle or knob adapted to serve as guiding means in the manipulation of the plane.

3. A router plane comprising in combination inner and outer sections, hinged together at one end, spring held means connecting said sections near the opposite end and tending to hold the sections together, adjustable means operating at right angles to the base of the plane for opening said sections from each other and an adjustable cutting tool carried by said inner section, substantially as described.

In testimony whereof, I affix my signature in presence of two witnesses:

CHAS. FINK.
